UNITED STATES PATENT OFFICE.

JOHN W. DEWEES, OF PHILADELPHIA, PENNSYLVANIA.

SEWING-MACHINE.

SPECIFICATION forming part of Letters Patent No. 432,746, dated July 22, 1890.

Application filed August 22, 1889. Serial No. 321,573. (Model.)

To all whom it may concern:

Be it known that I, JOHN W. DEWEES, a citizen of the United States, and a resident of the city of Philadelphia, in the county of Philadelphia and State of Pennsylvania, have invented certain new and useful Improvements in Sewing-Machines; and I do hereby declare the following to be a full, clear, and exact description of the invention, reference being had to the accompanying drawings.

My invention has relation to high-speed sewing-machines of the class which operate to produce a double-chain or elastic stitch in the material to be sewed, and has particular relation to that portion of such machines which controls the movement of the looper for the lower thread, and has further relation to the take-up for said lower thread.

My invention has for its object to improve and simplify the construction and increase the efficiency of the aforementioned looper-operating mechanism and take-up.

Heretofore the movement of the looper around the vertical axial line of the needle in machines of the above-mentioned character has been obtained in various ways—for instance, by the use of a rocking frame journaled at both ends and oscillated in a vertical plane by a cam on the main shaft, on which frame is journaled a crank to which is pivotally connected the needle-arm pitman and on which is supported the looper, the result obtained by this construction being the said movement of the looper around the needle while rocking in response to the swing of the rocking frame.

My invention consists in the provision of a straight lever journaled on a vertical stud on the base-plate of the machine and having formed thereon at its center diametrical oppositely-extending arms for the reception of said stud, said lever being adapted to oscillate horizontally in response to the motion of a ball or round-edged eccentric on the main shaft and a connecting-rod therefor attached to the inner end of said lever by a ball-and-socket joint. The outer end of this lever is formed with a vertical T-shaped head, having a socket therein for the reception of and in which is journaled a stud, in the upper end or head of which stud is secured the looper.

This stud has an outwardly-extending horizontal arm, passing through a slot in the wall of said socket, provided with a ball on its outer upturned end, which ball is secured and has its bearing in a socket in a shell or casing on the outer end of the needle-arm pitman, said pitman imparting the longitudinal reciprocating movement to the looper through the ball-arm and the stud in which said looper is secured, while the eccentric and rod are imparting the transverse movements to the looper, the result being a regular movement of the looper curvilinearly in a horizontal plane, describing an ellipse around the vertical axis of the needle.

My invention further consists in the provision of a novel form of take-up for the lower thread, consisting of a straight bar pivotally secured at one end to the needle-arm pitman with liberty of movement horizontally, and at its other end slides between a pair of upturned lugs on the end of a laterally-projecting arm on the central-bearing portion of the looper-operating lever, said lugs having each an opening therein for the passage of the thread, and said arm of course moves in response to or coincidently with the movement of said lever. Secured on the upper surface of the straight bar is a block or lug with an opening parallel with and for the same purpose as the openings in the two first-mentioned lugs on the arm, said block being so disposed relatively to said lugs as to bring their openings into alignment at one extreme of the movement of the needle-arm pitman, and when said pitman is making the first part of its return movement the eccentric which actuates the looper-operating lever will cause said lever to remain for an instant at rest along with the arm on which the take-up bar slides. Thus the surplus slack in the thread will be taken up before the said arm begins to move, which latter movement is not in any case more than very slight and not nearly so great as that of the block on the said bar.

All the details of my invention will be more specifically described in the specification hereinafter and will be clearly understood upon reference being had to the accompanying drawings, wherein—

Figure 1 is a side elevation of a sewing-ma-

chine with my improvements applied thereto, and Fig. 2 is an end elevation of the same. Fig. 3 is a plan view of that portion of the machine shown in Fig. 1 below line yy . Fig. 5 is a vertical transverse section on line xx of Fig. 3. Fig. 5 is a vertical longitudinal section of a detail.

10 A represents the needle-arm, B the head, C the needle-bar, D the base-plate, c the needle, E the fly-wheel, and F the connecting-rod between the fly-wheel eccentric and the needle-arm, all of which are of usual construction and need not be particularly described.

15 G represents the looper-operating lever provided with the vertically-extending oppositely-disposed arms g g' , which are cast integral therewith or may be secured thereto. Said arms have a longitudinal opening therein 20 for the reception of the stud H, (shown in dotted lines,) secured vertically on the base-plate and affording the central bearing for the lever G, said lever being secured thereon by the screw H' passing into said stud and 25 having a bearing at its lower end on the base-plate D. Lever G is provided also, with two horizontally-extending oppositely-disposed arms or extensions g^2 g^3 at right angles with and about midway of the ends of arms 30 g g' . The inner arm g^2 is formed into a ball-shaped or rounded bearing for one end i of the connecting-rod I, the other end i' of said rod being secured on the eccentric I' on the main shaft K, while the outer arm g^3 35 is formed with two vertically-extending oppositely-disposed arms g^4 g^5 , similar to arms g g' at its end, said arms forming a T-shaped head for the lever G. The arm g^5 , being the lower one, is of a length sufficient to allow of 40 the oscillation of the lever without said arm contacting with the base-plate. In this T-shaped head or in the arms g^4 g^5 is formed a socket g^6 for the reception and journaling therein of the stud L, with the enlargement 45 or head l formed thereon, said head having a socket l' for the securing therein of the looper L', which is of usual shape, and said stud having secured thereto or integral therewith or in a socket l' therein a lateral arm M, 50 which passes through a transverse slot g^7 in the wall of the socket g^6 . The outer end of this arm is upturned, as at m , and has secured thereon or integral therewith the ball m' , which is secured and has its bearings in the 55 shell N on the outer end of the needle-arm pitman N' by means of the screw or plug n , the upturned end m passing through a slot n' in the under side of said shell, and said pitman is secured at its inner end to the 60 needle-arm A in the usual manner. Thus, it will be readily understood, movement of the eccentric I' and rod I will cause the lever G to oscillate horizontally on its stud H in a horizontal plane, accomplishing the movement of 65 the looper from front to rear of the needle, and vice versa, while the needle-arm pitman N', through the ball m' and arm M, is trans-

mitting an oscillating movement to the stud L and the looper L', which movement causes the said looper to travel in its proper paths at the front and rear of said needle, and the movements of said pitman and eccentric-rod are so timed that the motions of the looper will be in a horizontal plane in a regular curvilinear path around the needle. 70

75 O represents the take-up bar, extending nearly parallel with the needle-arm pitman and secured pivotally to a collar n^2 on said pitman by means of the screw o near its inner end, and having on its upper surface 80 near its outer end the upright block o' , provided with the thread-opening o^2 . This bar, at its outer end beyond said block, is retained by and secured between the upwardly-extending lugs or forks g^8 on the outer end of 85 the rigid arm G', said arm being cast integral and moving correspondingly with the central bearing of the lever G, and said forks having notches g^9 therein for preventing the dislodgment of the bar O. Said forks have 90 also thread-openings similar to the opening o^2 and parallel therewith, in order that when the block comes between the forks said openings will be in exact alignment.

95 P represents the stop or tension for the lower thread R, which consists of the horizontal double-tongued spring-arms p with the offset or ears p' thereon, said stop being secured to the standard Q on the base-plate D by the screw p^2 , said tongues being intermittently opened and closed at proper intervals by the eccentric K', which contacts with the lower one of tongues p . When the tension is on the thread R, the take-up bar O, with its block o' , will recede, while the forked arm 100 G' remains temporarily stationary, and take up the slack in said thread between the take-up and the looper L', after which taking up the arm G' follows the bar O until it reaches the extent of its movement in that direction, 105 the result being a much quicker taking in of the slack in the thread with a less movement of the take-up, than heretofore.

110 S represents the eccentric-rod, which is connected by the screw s to the link T of the four-motioned feed mechanism and is actuated by the eccentric S' on the main shaft, the operation of which and the construction of these being substantially as heretofore, and need not be further described.

115 I am aware that the idea of intermittently stopping and releasing the lower thread as an adjunct to the operation of the take-up is old, as is also the specific form of stop shown in the drawings of my invention. Therefore I 120 do not wish to be understood as claiming the same.

125 What I claim as new, and desire to secure by Letters Patent, is—

1. In a sewing-machine, the combination, 130 with the needle and feed mechanism, of a pivoted lever actuated by an eccentric on the main shaft and having arms g^4 g^5 , the socket g^6 and the slot g^7 in said arms, the stud L,

the looper L', the arm M, and a pitman connecting the latter and the needle-arm, substantially as shown and described.

2. In a sewing-machine, the combination, 5 with the needle and the feed mechanism, of the lever G, the arms g² g³, the stud H, the screw H', the eccentric I', the eccentric-rod I, the shaft K, the stud L, the arms g⁴ g⁵, the socket g⁶, the slot g⁷, the looper L', the arm 10 M, the ball m', the shell N, the pitman N', the needle-arm A, all combined for operation substantially as specified.

3. In a sewing-machine, the combination, 15 with the stitch-forming and feed mechanism and a stop or tension for the lower thread, of the bar O, pivoted at one end on the pitman N', the forks g⁸, the notches g⁹, the block o', the thread-openings in said forks, and the 20 opening o², all combined for operation substantially as described.

4. In a sewing-machine, the combination, with the needle and feed mechanism, of the lever G, the arms g² g³, the stud H, the screw H', the eccentric I', the rod I, the arms g⁴ g⁵, the socket g⁶, the slot g⁷, the stud L, the 25 looper L', the arm M, the ball m', the shell N, the pitman N', the needle-arm, a stop or tension for the lower thread, the bar O, pivoted at one end on said pitman, the forks g⁸, the notches g⁹, the block o', the thread- 30 openings in said forks, and the opening o², all combined for operation substantially as described.

In testimony that I claim the foregoing I have hereunto set my hand this 21st day of 35 August, A. D. 1889.

JOHN W. DEWEES.
